Non-magnetic bodies are expelled from a zone of high flux density to zone of lower flux density in inhomogenous fields when oxygen enters the zones, the expulsion being against a very slightly biasing positioning means. A wire loop frame moves with the bodies to alter the inductive coupling between high frequency sending and receiving coils so that voltage induced in the latter varies with oxygen and concentration. The induced voltage is rectified and sent back to the loop which contains smaller loops situated in the fields so that the rectified feedback tends to urge the bodies back into the field. The regressive feedback is a measure of oxygen concentration.

**MAGNETIC GAS ANALYZER UTILIZING
INDUCTIVE MEANS TO SENSE DISPLACEMENTS
AND TO REBALANCE THE ANALYZER**

PRIOR ART

It has long been known to utilize in gas analyzers the characteristic that in the same inhomogenous magnetic field a material with a greater magnetic susceptibility will migrate to locations of greater flux density and the material with the lower susceptibility to the region of lower field strength. This action is therefore suitable in gas analysis because a few gases exhibit a distinguishing susceptibility. Oxygen e. g. has a susceptibility much greater than almost all the other gases, and so it is possible to manufacture a sensitive oxygen analyzer specific for oxygen.

In one conventional form of analyzer shown in German Pat. No. 947,932, there is a dumb-bell shaped expellable piece that carries at its two ends ball-shaped thickenings between the pole pieces of two U-shaped permanent magnets set opposite each other. The pole pieces are formed so that the magnetic field is inhomogenous and the whole arrangement is situated in a gas mixture from which the admitted components with different susceptibilities are to be determined. During the measurement for oxygen the oxygen molecules, due to their great susceptibility, preferentially enter the location of high flux density and expel therefrom non-magnetic glass end pieces or the dumb-bell. When the dumb-bell is mounted to turn about its transverse axis against a restoring force, the angle of turn is a measure of the proportion by volume of oxygen in the throughput gas.

It's also known to mount the dumbbell shaped expellable body on a wire loop. It is then possible to provide a mirror to move with the expellable body so that rays from a light source falls on the mirror and are reflected to a photo-electric cell to produce a current proportion to the deflection, which is fed back to the loop, after amplification if necessary, to oppose the tendency of the loop to turn. Thus the feedback or compensating current is a measure of the volumetric content of the magnetic gas in the sample.

Among the drawbacks to such a device was the fact that the light on the mirror must come from the outside and this presented many difficulties when the whole arrangement had to be situated in a gas-tight housing. Also the energy fed back from a sufficiently accurate photo-electric cell had to be produced and then amplified.

The invention has as its object a pickup or sensing of the deviation of the turning of such a loop mentioned and to provide the necessary compensation current by purely electrical means and providing an oxygen analyzer with fully automatic compensation and greater accuracy.

SUMMARY OF THE INVENTION

The invention is a device for the determination of magnetic gas especially oxygen concentration in a sample of gas having a deflectable or turnable wire loop or frame element provided with non-magnetic end pieces situated in the inhomogenous field zones between the poles of two magnets. The presence of a magnetic gas tends to expel the two end pieces and turn the loop. In the device, a tendency toward deviation by turning sets

up a compensating current flow in a means and tends to restore the loop to original position. Thus far the device is conventional; the novelty of the invention is in the combination of the preceding elements with an exciter or sending coil system fed by an oscillator, a receiver coil system, inductive coupling between the two systems being accomplished at least in part by way of the wire loop or frame carrying the non-magnetic end pieces.

It is advantageous to have the non-magnetic end pieces lie in an equatorial or horizontal plane, that is to say, a plane to which the flux lines of the magnet pole are perpendicular and remainder of the frame or loop constitute a coupling means, turnable about an axis perpendicular to the plane, between the two coil systems.

It is further advantageous that the loop or frame composes part of a deflectable system having two ends in a position to develop a magnetic field to coact with the inhomogenous field when a current flows in the loop and so enable compensation for deflection of the loop and at the same time have a portion of the frame act as coupling means between the coil systems.

The deflectable frame is mounted between tension strips which provide leads to the frame for compensation current. The frame may be considered as having two sides and current flows through each side of the frame in counter directions, that is, the frame as a whole develops no field. Indeed a homogenous field is produced without influence from the outside on the deflectable frame, since the action of the compensating current in both the vertical and horizontal parts of the frame cancels out each other.

DRAWING

FIG. 1 schematically shows a form of the invention with two possible means for the exciter coil system.

FIG. 2 shows circuitry for the invention with symbolic block forms as elements.

FIG. 3 shows a practical example of the circuitry in FIG. 2.

FIG. 4 is a graph showing the linearity of the relationship between compensation current or millevolts and deflection.

DESCRIPTION OF PREFERRED EMBODIMENTS

Basically the force F tending to expel a non-magnetic body from an inhomogeneous field where oxygen is present may be expressed by the following

$$F = K_{o2} \cdot V \cdot H (dH/ds)$$

where

H is the magnetic field strength

S is the displacement in the direction of the gradient of field strength

V is the volume of the non-magnetic body, and

K_{o2} is the susceptibility of the oxygen content in the mixture to be analyzed.

The force experienced on the non-magnetic body is proportional to the susceptibility of the gas mixture and hence, in practice proportional to the partial mass or pressure of oxygen in the gas mixture, since the susceptibilities of almost all other gases in the mixture are small enough to be disregarded. In the embodiment as

shown in FIG. 1, the non-magnetic body in which the force is exerted comprises two glass spheres 5 and 5'. These spheres can be hollow and vacuous or filled with a gas of known composition. The spheres are mounted fast on a torsion balance beam 6, preferably on a part integral therewith, the beam being as a wire frame with their horizontal projections as at 7 and 7' turned about 90° and embrasing the spheres equatorially.

The deflectable element or frame is suitably mounted by means of tension strips 8 and 8' so that the spheres are situated in inhomogenous magnetic fields between legs of two U-shaped permanent magnets 1 and 2, and 3 and 4 respectively having leveled end pole pieces 1', 2', 3' and 4'. The levels leave the gap between pieces 1' and 2' widening toward the rear and the gap between pieces 3' and 4' widening toward the front as shown in the drawing. Hence an inhomogenous field exists between both pairs of pole pieces. This means that the flux density between pole pieces 1' and 2' decreases from front to rear on the right in the drawing and from rear to front between pieces 3' and 4' on the left. When the non-magnetic spheres 5 and 5' are situated in the inhomogenous fields no force tends to move them horizontally as long as nothing is drawn into the spaces between the pole pieces to displace the bodies. However if a magnetic gas enters the vicinity of the spaces, the gas will preferentially be drawn into the zone of greater flux density and proportionally to the density of the flux to tend to expel the glass spheres. Due to the mirror image construction at the left and right of the magnet pairs a two-fold torque is exerted on the frame due to the expulsion force directions being in opposite directions.

The whole arrangement thus far described is enclosed in a gas-tight housing 9, outlined by dashed lines, provided with inlet and outlet means 10 and 10'. If gas having an oxygen content enters, the oxygen becomes correspondingly drawn into the zones of highest flux density and displaces the glass spheres and exerts a corresponding torque against the tension strips.

The entire balance beam is developed as a short circuit loop of electrically conductive material such as copper wire and includes as previously mentioned, two laterally projecting loops turned 90° with respect to the main flat plane of the frame for carrying the spheres.

According to the shown example of the invention a fixed cylindrical exciter transmitter or sending coil 12 is disposed so as to lie with its axis perpendicular to general location of the plane of the frame 6 and intersect it at or near the mid point of the area included by the frame. The coil 12 may be within the frame 6 or it may be in a recess in housing 9 where it can be closed off from the effect of corrosive gas. Coil 12 has flowing in it a high frequency current as from an external oscillator (See FIGS. 2 or 3), and as a result a high frequency voltage is induced in the wire frame 6. The value and phase of the induced voltage is dependent only to a negligible degree on the angular position of the frame relative to the coil 12 especially because the frame turns only on the order of 1°.

Instead of having the fixed sending coil at the middle of the wire frame 6 there can be, for example, two separate coils 14 situated parallel to each other under the wire frame. The two coils 14 can be connected in

series or parallel for being fed by an oscillator similar to oscillator 13. A high frequency voltage can be induced to the wire frame or balance beam 6 by either coil 12 or 14.

In a different location, one or more coils 15 may be situated, say, above the wire frame either inside or outside the housing 9 with the axis of the coil 15 lying perpendicular in space to that of the axis of transmitting or exciter coils shown at 12 or 14, and with this relative angular disposition there is absolutely no inductive coupling directly between the two coils 15 and 12 or 14. Coils shown as 15 serve as pickup or receiving coils and each is so disposed that a voltage is induced in either one or the pair by way of the wire frame 6, the voltage depending in magnitude and phase strictly linearly with the deviation by turning of the wire frame. Thus the magnitude and phase of the induced high frequency voltage in the coil or coils 15 is a measure of deflection of the wire frame 6. (See FIG. 3).

If the receiver coils of the pair 15 have their axes in the plane of the short circuit frame 6, they are inductively coupled to the coil 12 or 14 exclusively by the short circuit frame 6 when the latter is deflected.

As shown in FIG. 2, the output voltage from coil 15 is suitably led to an amplifier 16, preferably one of the so-called resistor capacitor feed back type with high amplification, the amplified output going to a phase correcting DC rectifier 17 from which a rectified output can be measured as a direct current. This direct current varies in direction with the direction of deflection of the frame 6 and the magnitude of the current varies proportionally with the degree of deflection. This current, which is a measure of the oxygen content of the gas sample within the housing 9, is suitably fed by means of the tension strips 8 and 8' to the balance beam, with rectified polarity, so that a force appears at the two projecting loops 7 and 7' surrounding the glass spheres 5 and 5'. This force, assuming proper polarity of the current, operates in the direction of graduation of the inhomogenous field strength. Since the current led to the frame 6 divides at the point of mounting the frame on the respective tension strips it flows in the two conductive projecting loops 7 and 7' situated between the respective pole pieces to produce a pair of forces. By having the proper polarity of the pole pieces this pair of forces is such that they form a couple to operate counter to the normal forces tending to push the glass spheres out from between the pole pieces when a magnetic gas is present. In this way the net deflection of the frame is made very small with only enough deviation to maintain the regressive current.

The system just described is a so-called torque compensation that corresponds somewhat to a torsion balance. The couple of forces to be compensated produces a torque which makes the deflection regressive until a quite negligible residual displacement or angle is obtained, which is necessary in order to produce the current used for the compensation. The requisite current for the compensation is a measure of the torque or force which acts counter to the expelling force on the glass spheres and therefore volumetric proportion of the gas to be measured. An indicating instrument interposed in the current path of the compensation current can be calibrated for volume percent of the gas present.

Other means may be used for energizing the frame, for example, the frame may have d.c. connection to the source of energizing current, or frame 6 may be energized by induction through a solonoidal coil going through the center of the wire frame. Also, as already mentioned, a second pair of rectangular shaped coils 14, can be used for energizing frame 6 turns of such coils 14 are arranged parallel to the wire frame 6. The coupling may be increased by the use of iron or soft steel cores in the stationary coils.

The receiving or pickup coils 15 can be connected in series or parallel but are so chosen in polarity that the signal induced in them by turning of the moving parts becomes amplified; Coils 15 are also connected to the exterior via a parallel connected capacitor, as shown in FIG. 3, having resonant frequency with the oscillator. A frequency of about 470 kHz gives satisfactory resonance.

FIG. 2 shows only in block fashion the assemblies shown in FIG. 3. The oscillator is made up of two transistors whose emitters circuits are connected together and is completely separated conductively from the remainder of the combination up to the conductors 18 which lead to the phase correcting rectifier. The transfer of signals from the sending coil 12 or 14 to the receiver coil 15 results exclusive by the position of the frame 6 as shown only schematically in FIGS. 2 and 3 and whose deflection is shown exaggerated.

The input signal passed on to the receiver coil 15 is further amplified by a two stage amplifier and the led to a phase correcting rectifier. This can, for example, be accomplished by a middle-tap transformer 19. Since the several component parts are self-evident further description is unnecessary: it is noted however that the output signal of the rectifier is preferably amplified by a DC amplifier with feedback.

In each case the compensation current flowing in the wire frame 6 maintains a predetermined orientation of the wire frame with its two glass spheres 5 and 5', nearly independent of the momentary prevailing oxygen concentration in the gas mixture to be analyzed.

It should however be noted that feed voltages are stabilized, in order that no inaccuracies occur due to unexpected variation in the oscillator voltage or in the amplification factors.

A further special advantage in forming the frame as a short circuit ring is that the D. C. flows in both halves somewhat relative to the projecting loops 7 and 7', so that due to the compensating current the moments acting on the glass sphere are equalized out in the same plane and location so there is no reaction force on the tension mounting strips. Moreover the invention is completely unaffected by stray outer homogenous magnetic fields from any direction, since the current flow is magnetically counter to each other in the two halves of the wire frame 6. This is true of the vertical parts of the frame as well as of the horizontal parts. Lateral movement of the expelled system i. e. the wire frame with the two sphere does not affect the null point or sensitivity.

Moreover, instead of the separate oscillator and subsequent amplifier for the induced voltage it is possible to employ a self-oscillatory amplifier and of course of such sign that the coils 15 and 14 influenced by their coupling due to the balance beam have self oscillatory

feedback. The limitation on oscillation for such an amplifier can be chosen so precisely that a mere turning of the balance beam system is sufficient to start oscillation. The oscillator voltage becomes rectified and fed back to the wire frame 6 for compensating effect. Here again the compensation current is a measure of the oxygen content in the sample gas. An advantage of this arrangement is that no sort of voltage stabilizer is necessary for the oscillator.

10 The invention claimed is:

1. In a magnetic gas analyzer wherein at least one nonmagnetic body is disposed on a deflectable carrier and being situated in an inhomogenous magnetic field, tending to become expelled and deflected from zones of greater magnetic flux density of the field with increasing concentration of a magnetic gas in the region of the field, and wherein a compensation current in the carrier produces a counter force tending to restore the deflected body to its undeflected position occupied prior to the increase of said concentration as the compensation current flows through the carrier for the body, the carrier upon deflection turning on an axis, the improvement comprising a stationary transmitting coil means;

stationary receiving coil means disposed in particular relation to the transmitting coil means; the carrier including a wire frame loop, extending in a plane that includes said axis and being disposed in relation to the transmitting and the receiving coil means for inductive coupling to the transmitting coil means and further for inductive coupling with the receiving coil means upon induction of current in the loop by the transmitting coil means and in dependence upon the relative angular position of the wire frame loop, the angular disposition of the wire frame loop being determined by deflection of said body and by the tendency to restore said body to said undeflected position;

first means connected for feeding an oscillating current to the transmitting coil means; and second means connected to said receiving coil means for deriving therefrom a signal representing the deflection of said frame loop and further connected for providing said compensating current in response thereto and feeding said compensating current to said carrier.

2. An analyzer as claimed in claim 1, wherein the carrier is symmetric to said axis and is provided with laterally projecting loops, each loop carrying one body, the loops being situated in two such inhomogenous fields, and two U-shaped magnets having pole ends of one opposite pole end of the other to form the two fields therebetween.

3. An analyzer as claimed in claim 2, the projecting loops of the carrier lying in a plane transverse to said axis and to the plane of said frame loop, the flux lines of the fields being perpendicular to the plane of the projecting loops, the frame loop of the carrier electrically connected to the projecting loops.

4. An analyzer as claimed in claim 3 and tension strip means for mounting the frame loop respectively at its sides, and the projecting for carrying compensating current to the frame and loops therein and permitting deflection of the frame about said vertical axis.

5. An analyzer as claimed in claim 3, the transmitting coil means including first and second interconnected coils the turns of the coils being substantially in planes parallel to that of the frame loop.

6. An analyzer as claimed in claim 3, the receiving coil means including first and second interconnected coils, the planes of turns of the receiving coils being substantially perpendicular to the plane of the frame loop.

7. An analyzer as claimed in claim 4 the second means including an amplifier connected to the receiving coil means for amplifying the voltage induced therein, and a phase correcting rectifier connected to the amplifier for rectifying the amplifier output, the output of the rectifier being connected to the two respective tension strips for supplying compensating current to the loops.

8. An analyzer as claimed in claim 4, said transmitting coil being a solonoidal coil in the middle of the frame.

9. An analyzer as claimed in claim 4, and a housing about the said magnets, frame and strips, the receiving coil means being outer of the housing, the turns of the receiving and transmitting coil means being substantially in mutually perpendicular planes.

10. In combination with an analyzer as claimed in claim 4, a housing around such analyzer, inlet and outlet means for passage of gas through the housing, the direction of travel of the gas through the housing being generally perpendicular to said turning axis of said frame.

11. An analyzer as claimed in claim 4 wherein the means for supplying the oscillating current to the sending coil is a self oscillatory amplifier and the sending and receiving coils are connected into the feedback circuit of the self oscillating amplifier whose rectified oscillatory signal output is connected to the wire frame.

12. Gas analyzer as in claim 1, wherein each of the transmitter and receiving coil means includes at least one coil having turns, and wherein the frame loop is disposed in a plane substantially parallel to the turns of the transmitter coil means, the turns of the coil of the receiving coil means being substantially perpendicular to the plane of the frame loop.

13. Gas analyzer as in claim 12, wherein a pair of bodies is disposed on the carrier and symmetrically to the axis, the frame loop being provided additionally with two projecting loops oriented in a plane transverse to the frame loop plane and respectively enveloping said bodies of the pair, the frame loop connected to said second means so that half of the compensating current flows through half of the frame loop at one side of the axis and through one projecting loop, and the other half of the compensating current flows through the other half of the frame loop and through the other projecting loop.

14. In a magnetic gas analyzer having at least one nonmagnetic body, the combination, a carrier for the body and mounted for providing deflection relative to an axis and including a wire loop extending in a plane that includes said axis;

means establishing an inhomogeneous magnetic field and effective on the body so that the body deflects the carrier on the axis in response to a magnetic gas tending to accumulate in zones of greater magnetic flux density thereby expelling said body;

means for providing an oscillatory magnetic field having a magnetic axis and disposed for energizing said wire loop and for inducing current flow therein;

inductive pickup means having a magnetic axis and disposed so that the magnetic axis runs parallel to said deflection axis, for picking up magnetic flux from the wire loop as resulting from the induced current flow in the wire loop, the picked up flux depending on the angular position of the wire loop in relation to said deflection axis, the pickup means providing signals representing said picked up flux; and

electric circuit means connected to the pickup means to be responsive to the signals developed in the pickup means as resulting from said picked up magnetic flux, and providing a d.c. current to the carrier in dependence upon the picked up signals to be effective adjacent said body for counteracting said deflection as resulting from said expelling.

15. In an analyzer as in claim 14, wherein said carrier includes a second loop extending from said wire loop and in a plane transverse to the plane of said wire loop, said second loop enveloping said body and providing a magnetic field effective in and superimposed upon said inhomogeneous field in response to the current in the carrier.

16. In an analyzer as in claim 14, and having two nonmagnetic bodies wherein the carrier includes a pair of relatively small loops extending from said wire loop and in a plane transverse to the plane of said wire loop, said small loops enveloping said bodies and respectively providing magnetic fields effective in and superimposed upon said pair of inhomogeneous magnetic fields, and together counteracting said deflection resulting from the expelling of the bodies by the magnetic gas in each said fields, the d.c. current being fed into said wire loop for flow through said small loops and being magnetically ineffective as to inductive coupling of the wire loop to the pickup means.

17. In an analyzer as in claim 16, said pickup means including a pair of coils disposed symmetrically to said axis adjacent said wire loop and each with a magnetic axis parallel to said deflection axis.

18. In an analyzer as in claim 16, wherein said wire loop extends in a plane transverse to the magnetic axis of the means for providing an oscillatory magnetic field.

19. In an analyzer as in claim 14, wherein said wire loop extends in a plane transverse to the magnetic axis of the means for providing an oscillatory magnetic field.

20. In a magnetic gas analyzer having a pair of nonmagnetic bodies, further having means to establish two inhomogeneous magnetic fields;

a carrier for suspending said pair of bodies for rotation on an axis and respectively in the two fields, the fields effective on the bodies so that they deflect in similar rotational directions on said axis in response to a magnetic gas tending to accumulate in zones of greater magnetic flux density thereby expelling said bodies;

the carrier including a short circuited frame loop extending in a plane that includes said axis, further including a pair of projecting loops symmetrically disposed to said axis and extending from and being

integral with said frame loop, said projecting loops extending in planes transverse to the plane of the frame loop, the projecting loops respectively extending around said bodies; means including at least one transmitter coil and disposed for inducing current in the frame loop which, when flowing through the projecting loops, produces self-compensating, oppositely directed magnetic interaction with said inhomogeneous fields not causing deflection of the frame; pickup means, including at least one coil and inductively responsive to deflections of the frame loop about said axis; and circuit means connected to the pickup means and providing a d.c. current representative of said response of said pickup means, and feeding said d.c. current to said frame loop thereof, to be effective in the two projecting loops for similarly

directed interaction with the inhomogeneous magnetic fields tending to restore undeflected position of the two bodies as suspended by the carrier.

21. In an analyzer as in claim 20, wherein suspension means for the frame loop suspends the frame loop in said axis and at opposite ends of said frame loop, said d.c. current being fed into the frame loop through the suspension means, the d.c. current branching into first and second portions to flow in opposite directions through the frame loop portions in relation to the axis, the first and second portions respectively flowing through the projecting loops.

22. In an analyzer as in claim 21, wherein the pickup means include a pair of coils each having magnetic axis parallel to the axis of said carrier, and respectively disposed in the vicinity of said frame loop portions on one and the other side of said axis of said carrier.
